[57] CLAIM

The ornamental design for a flexible razor cartridge, as shown and described.

DESCRIPTION

FIG. 1 is a top, front perspective view of a flexible razor cartridge showing my new design;

FIG. 2 is a right side elevational view thereof, the side opposite being a mirror image of the side shown;

FIG. 3 is a top plan view thereof;

FIG. 4 is a front elevational view thereof;

FIG. 5 is a rear elevational view thereof;

FIG. 6 is a bottom plan view thereof; and,

FIG. 7 is a perspective view shown mounted on a razor handle.

The broken line showing of the razor handle in FIG. 7 is for illustrative purposes only and forms no part of the claimed design.
